UNITED STATES PATENT OFFICE.

WARREN H. TAYLOR, OF STAMFORD, CONNECTICUT, ASSIGNOR TO THE
YALE & TOWNE MANUFACTURING COMPANY, OF SAME PLACE.

AUTOMATIC VENDING-MACHINE.

SPECIFICATION forming part of Letters Patent No. 647,997, dated April 24, 1900.

Application filed November 10, 1898. Serial No. 696,079. (No model.)

To all whom it may concern:

Be it known that I, WARREN H. TAYLOR, a citizen of the United States, and a resident of Stamford, in the county of Fairfield and State 5 of Connecticut, have invented certain new and useful Improvements in Automatic Vend-
ing-Machines, of which the following is a specification.

My invention relates to automatic vending-
machines in which the movement necessary
to set them in operation is imparted by hand
through a suitable lever, and more particularly to that class of vending-machines which
operate to deliver one or another of certain ar-
ticles contained therein, according to the point
where the mechanism is arrested and which
is generally determined by the character of
the coin or token introduced. In machines
of this character, as well as in other machines
operating automatically, unauthorized con-
trol over the machine is sometimes exercised
by back pressure or other manipulation of the
actuating-lever.

The object of my invention is to provide an
actuating-lever through the medium of which
the intended operation may readily be effected,
but which will exercise no retarding or
other control over the machine after the parts
are once moved to the point beyond which
they operate automatically.

To these ends my invention consists in
mounting the lever loosely upon the shaft of
the mechanism which it is intended to oper-
ate and in establishing turning connection
35 between said lever and the shaft or other part
to be moved through the medium of a pin
carried by one of the parts and a slot provided
on the other.

My invention further consists in certain
40 novel details in the construction of the parts
whereby the above-mentioned features are
suitably embodied in effective mechanism.

In the accompanying drawings, Figure 1
represents a partial side elevation of a vend-
ing-machine in which some of the automatic-
ally-operating parts are merely for purposes
of illustration shown by dotted lines, while
the parts wherein my invention lies are shown
in full lines. Fig. 2 shows by face and edge
50 views an operating-lever constructed in ac-
cordance with my invention. Fig. 3 shows

by face and sectional views the hub, which
is fixed upon the shaft and which receives the
operating-lever. Figs. 4 and 5 are views re-
presenting the retaining-nut and washer em- 55
ployed in carrying out my invention.

1 represents the casing or housing of a vend-
ing-machine of any character, which for pur-
poses of illustration is assumed to be provided
with a cylinder or reel 2 for supporting the 60
goods to be vended, a detent or lever 3, which
is held by a spring 4 into engagement with the
reel to prevent its movement and which is
limited in its movement by stop 5 and which
is normally held against displacement by a 65
dog 6, having a controlling-spring 7. I have
also shown, as suggestive of apparatus to be
controlled, a toothed segment 8, which is the
part for controlling the movement of the de-
livery-reel and which is to be moved by the 70
lever forming the subject of my invention to
one limit of its movement and thereafter re-
turned automatically to such a position as is
previously determined by the coin or token
introduced, such return movement being ef- 75
fected by the spring closing and checking de-
vice 9, which is connected to said segment
through the medium of the arm and pitman
10. So much of the mechanism beyond be-
ing suggestive of parts to be operated, and the 80
specific character of which may greatly vary
in detail, forms no part of my present inven-
tion.

My invention comprises a suitable arm or
lever 11, adapted for prehension and mounted 85
upon a shaft 12, to which it may impart ro-
tary movement in one direction to an extent
determined by its limiting-stops 13 and 14.

15 represents a hub mounted by square
bearing or otherwise fixed against rotation 90
upon the shaft 12 and provided with a seg-
mental and concentric slot 16, which receives
a pin 17 on the lever 11 and extending con-
centrically about the shaft a distance equal
at least to the arc through which the lever 95
11 swings.

From so much of the description it will be
obvious that if the controlling toothed seg-
ment 8 is moved through the medium of the
lever 11 and pin 17 engaging in slot 16 to a 100
point where its movement becomes automatic
it is obvious that the movement of said seg-

ment cannot thereafter be controlled by back pressure through the medium of the lever 11 or by other manipulation of said lever.

The specific construction of the connection 5 between the lever 11 and shaft 12, whereby an initial movement may be imparted to the shaft through the lever, followed by a lost motion between said parts, will be more fully understood by reference to Figs. 2, 3, 4, and 10 5. The lever is provided with an elongated cylindrical bearing 18, which enters the annular socket 19 surrounding the arbor 20, upon which the socket of the lever fits, while the segmental slot 16 intersects the annular 15 socket and permits the pin 17 to be located contiguous to the bearing 18. The parts being thus accurately and firmly fitted together, the lever is held against displacement by means of nut 21, with interposed washer 22.

20 Having thus described my invention, the following is what I claim as new therein and desire to secure by Letters Patent:

1. In combination with the shaft of a vending-machine, a lever for actuating said shaft, 25 connected thereto by means of a hub, and a pin eccentric thereto on one of said parts and engaging the other, which permits the lever to impart to the shaft rotation in one direction only; substantially as and for the purpose set forth.

2. In combination with the shaft of a vending-machine, a lever having a hub for actuating said shaft, mounted to turn thereon, and a pin eccentric to said hub for limiting the movement of the lever upon the shaft; 35 substantially as and for the purposes set forth.

3. In combination with the shaft of a vending-machine, the hub 15 fixed against rotation upon said shaft and provided with the 40 arbor 20 and concentric slot 16, and the lever 11 fitted to turn upon said arbor and provided with the eccentric-pin 17, substantially as and for the purposes set forth.

4. In combination with the shaft 12 of a 45 vending-machine; the hub 15 fixed against turning thereon and formed with the central arbor 20, the surrounding socket 19 and the concentric slot 16; and the lever 11 provided with elongated cylindrical bearing 18 fitting 50 the arbor 20 and the socket 19, and with the eccentric-pin 17 working in the slot 16; said lever being secured upon said hub by suitable means, substantially as and for the purposes set forth.

WARREN H. TAYLOR.
